UNITED STATES PATENT OFFICE

ERNEST A. CONAWAY, OF LITTLE ROCK, ARKANSAS, ASSIGNOR TO JEAN H. CONAWAY,
OF CLAYTON, MISSOURI

SEAL

Application filed August 10, 1926. Serial No. 128,347.

My invention relates to a new and useful improvement in seals, and has for its object to provide a simple and highly efficient closure for a locking device which cannot be opened 5 while the seal is in place without first puncturing said seal, which puncture must be in such a position in order to open the lock as to be clearly observable upon even casual inspection. The locking device to which my 10 seal is adapted primarily is to secure two members together, such, for illustrations, as a freight car door to its jamb, the flap of a mail sack to the body of such mail sack, the gas controlling handle of a gas meter to the 15 fixed handle of the same, etc. In fact, my seal is adapted for use in a locking device where in tampering with such locking device it is desirable that knowledge of the same may be had upon even casual inspection of the 20 seal.

My seals may be formed in single units, or they may be formed in strips duly perforated at their junction so as to be readily separated for use, or they may be formed in any 25 other convenient manner.

Fig. I is a front view of one of my improved seals.

Fig. II is a front elevation of that portion of one type of lock which I employ and 30 which I designate as the "keeper", with my seal inserted therein.

Fig. III is a cross sectional view similar to Fig. II somewhat enlarged.

Fig. IV shows a series of my improved seals 35 in strip form and duly perforated at the intersection of the seals.

Fig. V is a front elevation of my seal formed as a single unit.

In the drawing A designates a seal formed 40 out of any desired material, such as a tin-coated metal, terne plate, or other non-rusting metal or of relatively thick waterproof card or fiber board which may be relatively easily punctured when it is desired to unlock the 45 locking device, but which puncture remains clearly observable upon even casual inspection.

1 designates the upper or sealing portion 50 of my seal having lugs or ears 2 and 3 projecting from each side thereof at the sealing

end of my seal. 4 is a skirt depending from the upper portion 1, and 5 is an aperture by which the seal may be threaded upon a wire or other suitable carrying device. 6 designates a space which is preferably lightly 55 blocked out to mark where the puncture should be made. When employed I do not make it so pronounced as to confuse the same with a puncture when the seal is casually inspected. At 7 may be inserted the name of the 60 owner of the device to be locked and sealed, and at 8 the serial number of the seal may be placed when so desired.

B designates that portion of a locking device which I term the "keeper". It is to be 65 understood that I am illustrating merely one type of locking device keeper, which may be changed depending on the particular use to which the locking device is to be put. C are cams within said keeper near the front face 70 thereof. D is an aperture in the front portion and communicating with the interior of said keeper. E are shoulders above said cams as appear most clearly in dotted lines in Fig. II. The locking member (not shown) is adapted 75 to enter said keeper at F and is adapted to close such entrance and thereby prevent the removal of the seal, which is shown in said keeper in Figs. II and III.

The seal is first inserted in the keeper B, 80 the lugs or ears 2 and 3 fitting over the cam C whereby said seal may be pressed forwardly approximately against the front inner portion of said keeper and immediately adjacent the opening D. When the seal has 85 been so placed and with the inscriptions thereon observable through the opening D in the keeper A, the locking member of the locking device is inserted through the opening F and the locking lugs thereon (not shown) 90 pass over the tops of the cams C. This effectually locks said seal in position and the locking member can only be released by puncturing the seal with a suitable tool whereby the locking lugs may be released from said 95 cams. I may form my seals with the lower portion of the skirt 4 cut away as shown at 9.

I claim:

1. A seal comprising a portion adapted to close an opening in a locking device, shoulders 100

projecting laterally from the side edges of said seal, and a skirt portion depending from said seal beneath said shoulders, said seal being also provided with an indicating mark where puncture should be made to unlock
5 said locking device.

2. A seal comprising a portion adapted to close an opening in a locking device, shoulders projecting laterally from the side edges
10 of said seal, and a skirt portion depending from said seal beneath said shoulders, said skirt portion being apertured so that said seal may be threaded upon a carrying device.

In testimony that I claim the foregoing I
15 hereunto affix my signature.

ERNEST A. CONAWAY.
